UNITED STATES PATENT OFFICE.

FRANK JEWETT, OF HARTFORD, CONNECTICUT, ASSIGNOR TO OWEN H. JONES, OF SAME PLACE.

BALL-COCK.

SPECIFICATION forming part of Letters Patent No. 663,231, dated December 4, 1900.

Application filed September 18, 1899. Serial No. 730,864. (No model.)

To all whom it may concern:

Be it known that I, FRANK JEWETT, a citizen of the United States, residing at Hartford, in the county of Hartford and State of Connecticut, have invented new and useful Improvements in Ball-Cocks, of which the following is a specification.

My invention relates to the class of devices which are particularly adapted for use in connection with apparatus for supplying water in buildings in which tanks, pipes, and ball-cocks are used; and the object of the invention is to provide a simple and compact form of valve easily accessible for repairs and operative under varying pressures and by means of the ordinary float and lever commonly used with ball-cocks of this general class.

Referring to the drawings, Figure 1 is a top view of the ball-cock, showing the valve-body cut away in horizontal section. Fig. 2 is a view in central vertical section through the structure. Fig. 3 is a plan view of the removable valve-seat and in cross-section through the valve-body.

In the accompanying drawings the letter *a* denotes a valve-body having a chamber *b*, a water-inlet *c*, and an outlet *d*, the latter being arranged (in the form of the present embodiment of the invention) at the side of the chamber *b* which is in line with the inlet-opening *c*. The chamber *b* is larger in diameter than the inlet *c*, and a cap *e* is secured, as by means of screws *f*, to the valve-body at one end. The cap *e* has a flange or shoulder *e'*, that enables a close joint to be formed between the parts. A tubular projection *g* on the inner side of the cap is of a suitable length to bring its edge into close contact with the removable valve-seat *h*, which is closely fitted in a socket *a'* in the bottom of the chamber *b*, a packing-ring *i*, of suitable material, being borne on the rear of the seat *h* and forming a somewhat-elastic bearing-surface for the end of the projection *g*. This removable seat *h* may be made of the same form on its opposite faces, so as to be reversible on the seat. The flange *g'*, that projects from the part *g* within the chamber and extends to the inner surface of the wall, forms a guide that aids to properly center the valve *k*, the shank *k'* of which extends through the cap *e*, and it also forms a shield to pre-

vent the water from flowing against the under surface of the cap with a velocity or under a pressure which would cause the unpacked joint at the edge of the cap to leak.

The valve *k* reciprocates within the chamber or space in the enlarged inner end of the projection *g*, and the ports *g²* *g³*, formed through the wall of this part, provide for the free flow of water to the outlet *d* when the valve *k* is lifted from its seat.

On the outer surface of the cap *e* a bracket *l* supports a lever *m* by means of a pivot-pin passing through the parts, and a roller *n* on a pin *n* on the valve-spindle *k'* is located in the slot *m'* in the lever *m*, so that as the lever is rocked on its pivot the valve-spindle is reciprocated. A float-lever *o* is secured to the other arm of the lever and is moved by means of the usual float, that is controlled as to its position by the water-level within the tank to which the ball-cock is attached, it being of course understood that the valve-body *a* is provided with suitable means of attachment to a tank and to a supply-pipe.

The operation of the device will be readily understood from the foregoing description of the several parts and their related positions in the combination.

What I claim as my invention, and desire to secure by Letters Patent, is—

In a ball-cock in combination, a valve-body having a chamber, a water-inlet at one end of the chamber, an opening at the opposite end and an outlet at the side of the chamber, a cap adapted to close the opening in the chamber and having a tubular projection extending inward toward the inlet side of the chamber with its inner end resting against the valve-seat, a flange on this projection extending to the inner surface of the wall of the chamber and forming a guide and shield, said flange being located between the edge of the outlet and the cap, openings through the wall of the tubular projection, a plunger-valve having its spindle supported in said cap and tubular projection and adapted to close the inlet, means for securing the cap in position, and means for operating the valve-spindle.

FRANK JEWETT.
